UNITED STATES PATENT OFFICE.

OLIVER VANORMAN, OF RACINE, WISCONSIN.

SEAT FOR VEHICLES.

SPECIFICATION forming part of Letters Patent No. 254,412, dated February 28, 1882.

Application filed December 10, 1881. (No model.)

To all whom it may concern:

Be it known that I, OLIVER VANORMAN, of Racine, in the county of Racine and State of Wisconsin, have invented certain new and useful Improvements in Seats for Vehicles; and I do hereby declare the following to be a full, clear, and exact description of the invention, such as will enable others skilled in the art to which it pertains to make and use it, reference 10 being had to the accompanying drawings, which form part of this specification.

My invention relates to an improvement in seats for vehicles; and it consists in making the frame or support for each end of the seat 15 of an iron casting, which is provided with suitable flanges around its edges for the purpose of strengthening the frame or support, and which has pivoted upon its lower edge a suitable clamping or other fastening device for 20 the purpose of securing the seat in place upon the top of the wagon-bed.

The object of my invention is to provide a light, strong, and ornamental support for the seat, which will form a permanent means of 25 advertising.

Figure 1 is a side elevation of my invention. Fig. 2 is a vertical section of the same, and Fig. 3 is a perspective.

A represents the frame or support, which is 30 to be secured to each end of the seat, and which is formed of a light metallic casting, of which the name or the initials of a name will form a permanent part, as shown. By thus casting the name or the initials as a part of 35 the frame in light ornamental open-work the seat forms a permanent means of advertising for the manufacturer or any other person or thing that may be preferred. Upon the top of this frame or support, on its inner side, is 40 formed the flange B, which is preferably made wider at its ends than the center, and through which flange are made suitable bolt-holes, through which the clamping-bolts which fasten the seat and the support together are passed.

45 Around the inside edges of both ends and the bottom of the frame are formed the flanges C, which serve to brace and strengthen the frame.

50 Projecting down from the flange which is made along the inside bottom edge of the frame is the support D, which has its lower

end turned at right angles, so as to extend horizontally outward for the purpose of having the clamping or fastening device S pivoted to it. In order to strengthen this support for the clamping device, there is a flange, G, at 55 each of its ends, which extends inward from the frame and at right angles to it, and which flange projects down over the side of the support, as shown, so as to brace and strengthen the support against the pressure of the clamping device that is brought to bear upon it. These two flanges G extend a considerable distance above the bottom flange of the frame, and extend inward from the frame the same distance that the bottom of the support is 60 turned outward.

The fastening or clamping devices by means of which the frame is fastened to the top of the wagon-bed may consist of a simple cam, as here shown, or may be of any construction, 70 that may be preferred. When the frame which supports each end of the seat is placed upon the top of the wagon-bed the support to which the fastening device is pivoted projects downward inside of the bed a suitable distance, so 75 that the fastening device can get a good hold upon it. The fastening device must first be turned outward, so as to allow the support to sink down inside of the bed, and by turning the device in such a manner that its cam end 80 will catch against the side of the bed the frame will be locked rigidly in place. Also, projecting downward from the rear end of the frame A is a suitable lip or projection, I², which also catches inside of the wagon-bed while the 85 lower flat edge of the frame A is resting upon the top edge of the bed, and thus serves to hold the seat always in position.

The frame or support for a wagon-seat constructed as above described is very light, 90 strong, and durable, and serves as a permanent means of advertising, as described.

Having thus described my invention, I claim—

1. A frame or support for the end of a wagon-seat, provided with a wide flange upon its top edge, through which the clamping-bolts are passed, and with a strengthening-flange around its other edges, and suitable locks or projections for extending down inside of the 95 100

wagon-bed, one of which forms a support for the clamping device which fastens the seat in position, substantially as described.

2. A metallic frame or support for one end 5 of a wagon-seat, having the support for the clamping device in a single piece with it and the support braced by the flanges G, substantially as set forth.

In testimony whereof I affix my signature in presence of three witnesses.

OLIVER VANORMAN.
